SAFETY RAZOR AND BLADE

Joseph Muros, Cambridge, Mass., assignor to Gillette Safety Razor Company, Boston, Mass., a corporation of Delaware

Application January 27, 1944, Serial No. 519,899

10 Claims. (Cl. 30—65)

This invention relates to safety razors and consists in an improved blade of the thin flexible open-end type and in a novel combination of such blade with the blade-clamping members of a safety razor.

Open-end razor blades, that is to say, blades having a longitudinal slot opening out through one of the transverse end edges of the blade, may be employed in safety razors in which the cap and guard members are detachably connected, and such blades have the additional advantage that they may also be presented by endwise movement in any safety razor wherein the cap and guard members are connected to permit only a limited separation. Such razors are preferred by many users because by obviating the necessity of detaching and separating the parts of the razor the danger of misplacing or losing them is eliminated.

It has been found that in safety razors of the type wherein the blade is transversely flexed when it is clamped in shaving position, as in the "Gillette" type safety razors, the cutting edges of an open-end blade are frequently deflected out of their normal parallel relation. Whereas, the two sharpened longitudinal edges may be disposed accurately in parallel relation when the outline of the blade is initially determined, the two edges are often found to diverge toward the open-end of the blade when the blade is flexed and clamped in the razor. This is due partly to the fact that the hinge portion at the closed or solid end of the blade has a restraining effect on the two side portions which is entirely absent at the open-end of the blade. Going more into detail, the side portions are tied together at the closed end of the blade by a flexible connection which, when curved by the cooperating clamping elements of the razor, causes the cutting edges of the blade to draw together. However, inasmuch as the side portions of the blade adjacent to its open end are free and unconnected the free ends are not subjected to this drawing-in action. These differences in structure and behavior, and possibly other causes, often result in a departure from parallelism of the two sharpened cutting edges in an open-end blade when finally clamped in shaving position. Such variation detracts from the precision of the assembled razor and produces irregularities in the edge exposure of the blade that may even become so excessive as to be dangerous in some cases.

I have improved the structure and functioning of open-end razor blades and have solved the problem of uneven edge exposure by causing the

two side portions of the blade to draw together in the clamping operation until arrested by properly spaced stops or gauging surfaces. In effect I impress a drawing-together movement on the 5 free ends of the blade that compensate for the drawing-in of the other ends of the sharpened edges caused by the hinge connection between them. This I am able to do by lengthening or flattening a transverse arc in the hinge area or 10 in the solid end portion of the flexed blade, thereby causing the two side portions of the blade to swing toward each other at their free ends. An abutment or blade stop is located between the free ends of the blade and arranged to present 15 opposed outwardly directed stop or gauge faces. Under such circumstances the ends of the blade will continue to draw in until opposing inwardly directed gauging edges in the two side portions of the blade bring up against the outwardly directed stop faces of the abutment and so arrest 20 the movement of the side portions when each movement has progressed to the point where the sharpened cutting edges of the blade are exactly parallel.

25 The treatment of the open-end blade contemplated by my invention is effective only when the blade itself is supported or partially clamped in a condition of transverse curvature. I have discovered that having once given such initial transverse curvature to the blade the desired lateral shifting of the side portions may be caused by flattening and thus lengthening an arc in the hinge area of the already flexed blade. If the outer end of the hinge area be deflected about a 30 transverse axis and thus widened, the side portions are found to swing toward each other about axes located somewhere in the hinge area and near to the closed end of the blade slot.

35 This secondary or longitudinal flexing of the hinge area may be effected in any desired manner, but as herein shown and in accordance with another feature of my invention, it is effected by providing in the material of the hinge portion of the blade one or more projections so located as to be engaged and depressed by the concave clamping member of the razor, for example, one or more conical bosses may be struck from the material of the hinge and may project into position to be engaged by the inner face of 40 the cap member of the razor when the cap and guard members are clamped together. The portion of the hinge area containing the projection is thus flexed longitudinally in the razor and the desired compensating movement is thus imparted 45 to the side portions of the blade. Preferably and 50

as herein shown the projecting bosses may extend in opposite directions from the hinge area of the blade so that the same flexing of the hinge area will occur no matter which side up the blade is presented. It will be understood, of course, that the cooperating blade-clamping member is shaped to afford proper clearance for the flattening deformation which is impressed upon the blade.

It will be apparent, of course, that the same results may be obtained by providing a boss on the concave face of the blade-clamping member of the safety razor. This alternative construction is within the scope of the present invention.

These and other features of the invention will be best understood and appreciated from the following description of a preferred embodiment thereof selected for purposes of illustration and shown in the accompanying drawing, in which:

Fig. 1 is a plan view of a section of thin steel ribbon in which blades have been outlined;

Fig. 2 is a view in perspective showing a single blade in flexed position upon the convex guard member of a safety razor;

Fig. 3 is a view of the razor in end elevation showing a blade in cross-section, all on a greatly enlarged scale; and

Fig. 4 is a similar view showing a boss on the cap member of the razor instead of on the hinge area of the blade.

The preferred embodiment of the blade of my invention is best shown in Fig. 2. It is nearly rectangular in outline being sharpened in its opposite longitudinal edges 11 and provided with reentrant recesses in each of its corners. Two of these recesses form the elongated unsharpened end portion 12 at the solid end of the blade and in part define the hinge area therein. The blade is also provided with a centrally disposed longitudinal slot 13. This opens out through the outer transverse edge of the elongated unsharpened end portion at the open end of the blade. The slot 13 is designed to receive a blade-locating rib or projections of the cap member of a razor and to provide opposed inwardly-directed stop or gauge edges 18 adjacent to the open end of the blade. The slot merges into an intermediate circular enlargement 15 provided to receive the threaded stem of the cap. It has also other intermediate enlargements to receive blade-locating projections of the various designs found in other safety razors.

At the solid end of the blade the slot 13 terminates in a narrow transverse enlargement 14 which has the effect of distributing bending stress in the blade and defining the inner boundary of the hinge section. The hinge section is annealed and softened so that it may flex without breaking, while the remainder of the blade is hardened and tempered for cutting. At its open end the slot 13 flares somewhat to facilitate engaging the blade-locating projections when the blade is presented endwise and enters between the cap and guard members of the razor. In the material of the hinge area are provided oppositely directed conical bosses 16 and 17 which may be .003" to .015" in height. As shown in Fig. 2 the boss 17 projects upwardly and the boss 16 downwardly. These bosses are located symmetrically at either side of the longitudinal axis of the blade and substantially centrally between the outer and inner edges of the hinge area, although their location and distance from the

longitudinal axis may be varied considerably in practice.

In Fig. 1 is shown a portion of the thin flexible steel ribbon used in manufacturing blades like the blade 10 illustrated individually in Fig. 2. The steel ribbon is supplied in thicknesses between .003" to .007" and of the width desired in the finished blades. The blades 10 are first outlined in strip by punching the outline of the corner recesses and of the longitudinal slot 13. The bosses 16 and 17 are also produced at the proper points in the blade strip as it is advanced from one station to the next, either before or after the tempering step. The punched strip is hardened and tempered, annealed in the hinge areas 12 and ground, honed and stropped to produce the cutting edges 11 in the blade strip. Subsequently the individual blades 10 are separated from the strip on transverse lines, each line including or coinciding with the right-hand end of one of the blade slots 13 as seen in Fig. 1. A final smoothing operation on the transverse end edges of the blades produces the finished blade.

In Fig. 2 the blade 10 is shown as transversely flexed upon the guard member 20, shown as having a generally convex blade-supporting face. The guard 20 is substantially rectangular in outline being provided with downturned guard bars 21 at its opposite edges and longitudinal fulcrum shoulders 22. It is also provided with a longitudinal slot 23 and with a central perforation, corresponding to the aperture 15 of the blade, for the passage of the stem of the cap. The blade is of such length that its open end edge lies flush with or within the adjacent end of the guard.

The cap member 24 has a transversely concaved inner face which overhangs the fulcrum shoulders 22 and flexes the blade 10 over them by engaging it along lines within its cutting edges 11. It is provided with a centrally threaded stem 26 which passes through the guard member 20 and is engaged by a correspondingly threaded handle 27. The stem 26 is reduced in width immediately below the face of the cap to accommodate the width of the blade slot 13. The cap is provided with a pair of abutments or short ribs 25 which constitute blade-locating means and which provide outwardly directed stop or gauge surfaces to be engaged by the inwardly directed gauging edges 18 of the blade.

The blade as shown in Fig. 2 is represented as transversely flexed over the fulcrum shoulders 22 of the guard 20, that is to say, the hinge 12 is flexed transversely so that the two side portions of the blade defined by the longitudinal slot 13 are disposed at an obtuse angle to each other, but, in addition to this primary flexing about a longitudinal axis, or axes, the hinge 12 is subjected to a minute secondary flexing by the engagement of the cap 24 with the upstanding boss 17 of the blade. On this account the outer arc B of the hinge 12 is slightly depressed, being flattened and thereby transversely elongated. On the other hand, the inner arc A of the hinge 12 is not subjected to this secondary deflection but remains unchanged in its transverse dimension with the result that the two side portions of the blade are drawn or thrown inwardly toward each other at their free ends. The inner gauging edges 18 of the blade are thus brought into contact with and stopped against the outwardly directed gauge faces of the studs or rib 25 and the cutting edges 11 of the blade are,

therefore, held and maintained in condition of exact parallelism.

The exact location of the bosses 16 and 17 is of secondary importance so long as they serve to receive and transmit to the hinge area the pressure of the cap member 24. They may be located anywhere in the hinge area 12 and may be separated by substantially the full width of the hinge area if desired. It is however desirable to locate them symmetrically with respect to the major axis of the blade since this permits the blades to be conveniently stacked without attention to which face lies uppermost.

In Fig. 4 the invention is shown as embodied in a blade and razor combination wherein the boss 28 is transferred from the blade to the concave face of the cap member 24 of the razor. It is located centrally in the cap and in a position to engage the hinge area of the blade and impart to it the secondary longitudinal flexing which causes the two side portions of the blade to contract at their free ends or to compensate for any tendency toward spreading. As explained in connection with the bosses 16 and 17 the boss 28 may be located at any convenient spot where it will cause the outer arc of the hinge section to flatten when the blade is clamped in shaving position.

The outwardly directed faces of the rib 25 serve as stops for limiting the inward movement of the free ends of the two side portions of the blade 10 caused by the secondary deflection of the solid hinge 12. It will be understood that this flexing of the hinge causes a progressive compensating movement of the free ends of the blade which is arrested by the faces of the rib 25 only when the contraction has progressed to the point of rendering the cutting edges 11 exactly parallel.

Having thus disclosed my invention and described in detail two illustrative embodiments thereof, I claim as new and desire to secure by Letters Patent:

1. A double-edged, open-end blade for safety razors, having a body divided into similar side portions by a central longitudinal slot, the side portions being spaced apart at one end of the blade and having a solid connecting end portion at the other end of the blade, and a projection formed in the material of the said end portion.

2. A double-edged, open-end blade for safety razors, having a flexible body divided into side portions by a central longitudinal slot, and having a solid hinge portion connecting the side portions at one end of the blade, and projections formed in both surfaces of the said hinge portion.

3. A double-edged, open-end blade having a body of thin flexible steel slotted from one end and presenting similar side portions having opposed gauging edges at one end and a solid connecting hinge at the other end of the blade, and a conical boss struck out of the material of said hinge.

4. A double-edged, open-end blade having a body of thin flexible steel slotted inwardly from one end and presenting opposed side portions of equal length, said side portions merging into a solid hinge which limits the blade slot at its inner end, and a boss struck out of the steel of the hinge at a point spaced from its inner edge.

5. A double-edged, open-end blade having a body of thin flexible steel slotted inwardly from one end and presenting sharpened side portions connected at one end by a hinge area capable of flexing both transversely and longitudinally, and a contact projection located within the area of the hinge.

6. A safety razor having cooperating blade-clamping members shaped to impart transverse curvature to a blade interposed between them and a blade-locating projection disposed on one of said members, in combination with a flexible double-edge blade having a longitudinal slot opening through one end and a solid connecting portion at the other, and means for flattening an outer arc of said end portion when the razor members are clamped together and thereby drawing the side portions of the blade inwardly at their open end until arrested by engagement with said blade-locating projection.

7. A safety razor having cooperating members for clamping an interposed flexible blade in a position of transverse curvature between them, and a blade-locating stop at one end of one of said members, in combination with a double-edged open-end blade having a flexible hinge at one end and side portions which lie with said blade stop between them, and a contact projection on one of said members for flattening a part of the hinge when the blade is curved by engagement of said clamping members.

8. A safety razor having cooperating blade-clamping members with surfaces shaped for transversely flexing a blade interposed between them, and an interposed abutment presenting outwardly directed gauging faces, in combination with an open-end blade having a softened hinge portion at one end, and a projection from said hinge portion for imparting a longitudinal deflection to the already transversely curved hinge portion when the clamping members are drawn together and thereby drawing the open ends of the blade laterally against the gauging faces of the abutment.

9. A safety razor having blade-clamping members shaped to impart a pronounced transverse curvature to an interposed flexible blade, and a blade stop, in combination with an open-end blade having a soft hinge portion at one end, and means therein whereby a flattening deformation is imparted to the already transversely flexed hinge by clamping pressure of one of said members.

10. A safety razor having a guard member with parallel longitudinal fulcrum shoulders and a recess at one end, a cooperating cap member, and a stop on one of said members at the end opposite the recessed end of the guard member, in combination with a double-edged, open-end blade flexed transversely over said shoulders and embracing said stop at its open end, and means for flexing the closed end of the blade into the recess of the guard member thereby imparting a compensating contraction of its open end toward said stop.

JOSEPH MUROS.
